ATTORNEYS.

UNITED STATES PATENT OFFICE.

JAMES W. IVORY, OF PHILADELPHIA, PENNSYLVANIA.

TOOTH SEPARATOR.

Application filed July 1, 1922. Serial No. 572,157.

To all whom it may concern:

Be it known that I, JAMES W. IVORY, a citizen of the United States, residing in the city and county of Philadelphia, State of Pennsylvania, have invented a new and useful Tooth Separator, of which the following is a specification.

My invention consists of a tooth separator formed of a pair of arms pivotally connected, separating points on said arms, means on said arms for operating the same and consequently said points in opposite directions, and guides for said points, said arms having on their sides offsets, the advantages of which will be hereinafter described.

It consists also in providing the separator with an anchor which may be seated on a tooth adjacent to the teeth that are to be separated thus holding the separator firmly in position during the operation of separating the teeth, as will be hereinafter described.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a perspective view of a tooth separator embodying my invention.

Figure 2 represents an end view thereof.

Figure 3 represents a bottom plan view thereof.

Figure 4 represents a longitudinal section thereof on line 4—4 Figure 2.

Figure 5 represents a perspective view of the device detached from other members thereof.

Similar numerals of reference indicate corresponding parts in the figures.

Referring to the drawings.

1 designates a pair of arms which are connected at one end by the pivot 2 whereby the arms may be moved to and from each other. On the ends of said arms opposite to said pivot 2 are the separating points 3 which project towards each other and are adapted to enter between adjacent teeth to separate the same.

Freely fitted on said arms is the tubular yoke 4 in whose side are the elongated slots 5 which receive the adjacent portions of said arms and allow them to move therein in opposite directions. The ends of the yoke are internally threaded and to either end of

which is fitted the screw 6 which is adapted to bear against the side of the adjacent arm whereby by operating said screw said arm may be moved towards the opposite arm, and thus operate the points 3 in the separation of the teeth between which latter said points are adjusted, it being evident that said screw 6 may be applied to either end of the yoke as may be required.

Connected with the arms 1 at their pivotal ends is the spring 7 whose tendency is to move said arms and consequently the points from each other, this being occasioned when the screw 6 is rotated in reversed direction when the device is to be removed from the teeth.

8 designates the frame of the device, the same consisting of an inverted U-shaped plate in whose head 9 is fitted the screw 10 to whose lower end is swiveled the anchor 11 which occupies a position between the side legs 12 of said frame, said legs having on their ends the loops 13 which sustain said frame on the point and in which are freely fitted the points 3 whereby the latter may slide in said loops in their opposite directions and thus be guided true in their motions, and also serving when the points are in operative position to prevent twisting or irregular motions of the points.

The anchor 11 consists of a plate to which the screw 10 is swiveled and depending flanges 14 on the side ends of said plate forming a member which may be fitted on the crown of a tooth adjacent to the teeth to be separated and embrace the sides thereof, it being seen that when the points are presented to the teeth to be separated, the screw 10 is rotated whereby the anchor is engaged with the tooth that it is to occupy and is seated firmly thereon and thus the device is retained tightly in position and the frame 8 especially is prevented from shifting. Then the screw 6 is properly rotated and so the points 3 perform their separating operation. It will be seen also that the anchor may be secured in position prior to the operation of the separation of the teeth, and the separating points may be moved in opposite directions without disturbing the anchor, it being noticed that the frame 8 is freely mounted on the side arms 15 by its loops 13 receiving the separating points 3 and so said frame is sustained on said points and the latter are movable in and out of said loops without disturbing the

frame and consequently the anchor, as stated above.

The arms 1 have on their rear ends in-turned portions forming eyes in which the connecting pivot 2 is placed. The sides of said arms intermediate of said eyes and the points of the separator have thereon offsets 15 which form elbows whereby the rear portions of said arms are closer to each other than the forward portions which latter are thus spread apart to a greater extent, thus widening the space between the said forward portions.

The yoke 4 is mounted freely on said rear portions and may be adjusted longitudinally thereon while the offsets form shoulders which act as stops preventing the yoke slipping forward of said offsets and so limited in its motion toward the teeth, while also preventing the yoke from being improperly disconnected from the arms, especially in its assembled normal position whereby loss of the same is avoided.

The offsets in the lateral arms of the tooth separator not only give an advantage in lengthening the jaws of the separator without lengthening the slotted yoke or bow 4, but provides more width for the frame 8, Figure 5, the upright sides 12 of which have room between the contiguous teeth, and the arms of the separator giving free play when the points are brought into full action when the teeth are being separated which would not be the case if these offsets were not formed on the portions of the arms adjacent to the sides of the frame 8.

Having thus described my invention what I claim as new and desire to secure by Letters Patent, is:—

1. In a tooth separator, arms with separating points thereon, said arms having on their rear ends in-turned members having eyes therein, and a connecting pivot in said eyes, the sides of said arms having between

45
wardly extending offsets leaving the portions rearward of said offsets positioned close to each other, and the portions forward of said offsets positioned spread apart from each other to a greater extent than said rear portions, and a yoke freely fitted on said rear close-together portion between the said inwardly extending pivotal members and said offsets, the latter acting as stops to the forward motion of said yoke.

55
2. In a tooth separator having a side arm, and a separating point thereon, an anchor adapted to be fitted on a tooth adjacent to the teeth to be separated, said anchor being carried on a frame which is freely mounted on said side arm allowing the movement of said separating points without disturbing said anchor.

60
3. In a tooth separator, an anchor thereon adapted to be fitted on a tooth adjacent to the teeth to be separated, the same being provided with means for tightening it on said tooth, the side members of the frame of said anchor having thereon longitudinally extending loops in which the points 65
70
75
of the separator are freely fitted and guided.

4. In a tooth separator, separating points, arms carrying the latter, and an anchor on the frame thereof adapted to be fitted on and connected with a tooth adjacent to the teeth to be separated, thus holding the separator firmly in position during the adjusting and separating operations.

80
5. In a tooth separator, a frame, an anchor plate on the latter, and a screw-like member on said frame engageable with said plate adapting the anchor to be applied to a tooth adjacent to the teeth to be separated and firmly connected with the former.

JAMES W. IVORY.
